US00D855881S

(12) **United States Design Patent** (10) **Patent No.:** **US D855,881 S**
Hawes et al. (45) **Date of Patent:** **** Aug. 6, 2019**

(54) **ELECTRONIC VAPING DEVICE**(71) Applicant: **Altria Client Services LLC**,
Richmond, VA (US)(72) Inventors: **Eric Hawes**, Midlothian, VA (US);
Traci Martin, Richmond, VA (US);
Melissa Burroughs, Richmond, VA (US); **Berina Yerkic-Husejnovic**,
Richmond, VA (US); **Raymond Lau**, Richmond, VA (US); **Christopher S. Tucker**, Midlothian, VA (US); **Anthony Dibitonto**, Richmond, VA (US); **Marc Sauriol**, Richmond, VA (US); **George Stafford**, Richmond, VA (US); **Jamie Nicholson**, Richmond, VA (US); **Mark Breneman**, Richmond, VA (US);
Alistair Bramley, Richmond, VA (US)(73) Assignee: **ALTRIA CLIENT SERVICES LLC**,
Richmond, VA (US)(**) Term: **15 Years**(21) Appl. No.: **29/606,031**(22) Filed: **Jun. 1, 2017****Related U.S. Application Data**

(63) Continuation of application No. 29/545,534, filed on Nov. 13, 2015, now Pat. No. Des. 790,122.

(51) **LOC (12) Cl.** **27-99**(52) **U.S. Cl.**USPC **D27/194**(58) **Field of Classification Search**USPC **D27/100, 101, 162-170, 172-195;**
D24/110; D23/366

CLAIM

The ornamental design for an electronic vaping article, as shown and described.

DESCRIPTION

FIG. 1 is a perspective view of the electronic vaping device; FIG. 2 is another perspective view of the electronic vaping device;

FIG. 3 is a top view of the electronic vaping device

FIG. 4 is a bottom view of the electronic vaping device;

FIG. 5 is a first side view of the electronic vaping device;

FIG. 6 is an opposite side view of the first side view of the electronic vaping device;

FIG. 7 is a front view of the electronic vaping device; and, FIG. 8 is a rear view of the electronic vaping device.

In the drawings, the broken lines depict environmental subject matter only and form no part of the claimed design.
